FURNITURE DRAWER LOCK

James C. Siegel, New York, N. Y.

Application April 23, 1937, Serial No. 138,528

6 Claims. (Cl. 45—94)

This invention relates to mechanism for locking the drawers of a piece of furniture, such as a bureau or cabinet.

There has always been a demand for a good lock for furniture drawers, since most people find it very desirable to lock their drawers and thus prevent tampering with the contents thereof.

A very effective way of locking a series of drawers is to provide an individual lock for each drawer, but this is extremely expensive, if the locks are to be of good quality. A second way is to provide locking mechanism for locking all of the drawers, the mechanism to be controlled from a single point. This type of locking system is highly desirable because a very good grade of lock may be supplied and will control all of the drawers at the same time. Thus, in a system of this sort where there are eight drawers, one good lock will be sufficient for the entire eight drawers, while if individual locks are used, it is necessary to use eight locks for the eight drawers.

However, a drawer locking system of this preferred type has never been successful in medium or low priced furniture, because those locking structures of the prior art which have been devised so as to be made at a low price have been difficult to install and difficult to operate, while also giving considerable trouble. The prior art locking devices have also required special fabrication of the furniture to facilitate their application, and for that reason have failed commercially. I do not mean to confuse my invention with the type of locking system used on desks, where the locking of a single drawer controls all of the drawers, and where relatively expensive means are utilized. Systems of this type are too expensive to warrant their application to the average run of furniture and they require special construction of the furniture. This is also true of the type of system used on filing cabinets, which is also too expensive for use on ordinary furniture, and for that reason has never been applied to ordinary furniture.

While the main object of my invention is the arrangement of a locking system which will function perfectly, and will be easy to install on standard furniture, as well as inexpensive to manufacture, a further object of my invention resides in the arrangement of my locking system so that it will be unobtrusive and will not be objectionable in appearance when applied to modern furniture, which is usually made without obstructing portions and without a showing of hardware.

In my drawings, I show two modifications, Figs.

1 and 2 being partial front and side views respectively of a bureau utilizing either of my modifications. Fig. 3 is a partial elevation and section of the back of the bureau with the back cover plate removed therefrom. Fig. 4 is a section taken substantially along lines 4—4 of Fig. 3, while Fig. 5 is an enlarged view of a portion of Fig. 3, illustrating the mounting of the lock cylinder relatively to the bureau. Fig. 6 is a section through lines 6—6 of Fig. 3. Fig. 7 is a view similar to Fig. 3, illustrating a modification of my invention, while Fig. 8 is a view along lines 8—8 of Fig. 7. Fig. 9 is a partial section along lines 9—9 of Fig. 7 and showing parts of the assembly located in a plane above Fig. 9.

Referring now more particularly to the drawings, Fig. 1 shows the front of a modern type of bureau in which the drawers 10 have no handles, but rely rather on under-cut portions 11 for manual manipulation. Similarly, it will be noticed that none of the drawers have key holes of the type usually present in furniture equipped with locks. As shown in Fig. 2, the only locking device which is visible is the locking cylinder 12 at the extreme upper rear portion of the side panel 15 of the bureau.

In Fig. 3, I show the back of the bureau with the back cover plate 23 removed. The drawers 10 are seen to be resting on the horizontal wood partitions 13 in a manner well understood by those skilled in the art. The lowermost partition 13, shown in Fig. 3, is cut away as at 14 for the mounting of the vertical arm 15 of an L shaped locking bar. This locking bar is formed by the joining of a horizontal arm 16 to the vertical arm 15, as by a pivot 17, or else by welding. For holding the arms 15 and 16 in L shaped relation, an angular bar 18 is utilized, the bar functioning as will be quite clear to those skilled in the art. The upper partition 13 supporting the two small drawers is cut out at 19 to accommodate the vertical arm 15, and is further cut out at 20 to accommodate the angular bar member 18.

In order to hold the L shaped locking member 15, 16 securely in position so as to prevent its being forced outwardly by movement of one of the drawers forcefully against it, a metal plate 21 is secured by screws 22 to the lower partition member 13, and thus confines the arm 15, as will be readily understood. When several partitions 13 are used, each is treated as is the partition just described.

The back cover plate is designated by reference numeral 23, and is secured to the bureau in a

manner well understood by those skilled in the art. It will be readily appreciated that the back cover plate 23 may itself be used to confine the arm 15 relatively to the partitions.

5 A pair of depending guide brackets 24 are secured to the under surface of the upper panel of the bureau, as is best shown at 25 in Figs. 3 and 4, and mounted for sliding movement relatively to these brackets is the horizontal arm 16 of the L shaped locking member. Wood blocks 26 are also secured to the upper panel of the bureau and cooperate with the upper ends 27 of vertical locking bars 28 secured to the horizontal arm 16, and to the vertical arm 15 of the L shaped locking bar, whereby to better guide said bars. Each of the vertical locking bars 28 have horizontally extending lugs 29 which interlock with brackets 30 secured to each of the small drawers 18. Locking lugs 29 are carried by the vertical arm 15 of the L shaped locking bar and coated with brackets 30 secured to the series of large drawers which may be mounted in the bureau.

15 A spring 31 normally maintains the entire locking bar assembly and the parts carried thereby in the extreme left position illustrated in Figs. 1 and 3. When it is desired to lock up the structure, it is very simple to move the horizontal bar 16 to the right in Fig. 3 through movement of the locking 20 cylinder 12, which is pinned at 12a to the bar 16, as is probably best shown in Fig. 5.

25 The locking cylinder 12 is mounted for sliding movement in a sleeve 32, having a portion 32a fitting on the outside surface of the side panel of the bureau. The sleeve 32 has a bent over portion 32b which fits on the inside of the side panel of the bureau and is pinned thereto by pins 33. A locking bolt 34 carried by the cylinder 12 is adapted, in the position of Fig. 5, to lock the cylinder against movement to its dotted line position in the same figure, thus maintaining the cylinder and the bar 15, 16 in its locked position with the locking lugs 29 cooperating with the series of brackets 30. When the key plug of the cylinder 30 is operated in the usual manner thereafter to 35 retract the bolt 34 from its solid line position of Fig. 5 to its dotted line position in that figure, the locking lugs 29 will move with their supporting bars to the release position of Fig. 3.

40 I shall now refer to Figs. 7, 8 and 9 to describe a modification of my invention. In this modification, the locking is accomplished by the vertical movement of a main locking bar 50 and auxiliary locking bars 51, all of which carry locking lugs 52 cooperating with brackets 53 secured to the various drawers. Each of the usual drawer supporting partitions 54 is notched as at 55 in order to house the vertically moving bars 50 and 51, the said locking bars being retained in position by a series of plates 56 secured in covering relation to the said notched portions 55, and thus maintaining the locking bars against forcible projection from their proper aligned position relatively to the drawers by forceful rearward movement of the 45 drawers.

46 For imparting movement to the bars 50 and 51, I utilize a horizontal actuating bar 57 cooperating with a cylinder 12 in much the same manner as the bar 16 and the cylinder 12 cooperate in the 50 modification of Fig. 3. Pivoted to this bar 57 are a series of bell crank members 58, which in turn are pivoted at 59 to support members 60 secured to the lower surface of the upper panel of my bureau. At their opposite ends, the bell cranks 55 are pivoted at 61 to each of the vertical locking

bars 50 and 51, it being obvious that if the locking bar 57 slides to the right in Fig. 7, it will act to move the bars 50 and 51 upwardly into drawer locking position. When so actuated, the locking bar 57 will be locked in this locking position by the cylinder 12, in the manner described already with regard to the modifications of Figs. 3 and 5.

55 When it is desired to release the drawers, it is merely necessary to retract the bolt 34 of the cylinder lock 12 in the same manner as described with regard to Fig. 5, thus allowing the cylinder 12 to move to the left with bar 57 to its release position of Fig. 7.

From a reading of the description of my invention, it will appear quite clearly that all of the parts used therein are of simple design and of a type which may be fabricated in large quantities from inexpensive sheet metal stock. It will also be readily apparent that my invention may be readily applied to bureaus and other furniture of standard design, and without altering the appearance of the furniture and without requiring special fabrication and special provisions in the manufacture of the furniture to make my invention applicable thereto. I therefore believe myself entitled to a monopoly covering those equivalent structures which will readily occur to those skilled in the art.

I claim:

1. In a combination of the class described, a cabinet housing a series of sliding drawers, an L shaped bar, means mounting said bar for horizontal sliding movement in its own plane and with one arm in a horizontal position, the plane of said sliding movement being juxtaposed to the plane of the backs of the said sliding drawers, partitions between said drawers, means carried by said partitions for guiding said bar while preventing forceful pushing of said bar out of its plane of operation, locking extension pieces on said L shaped bar adapted to lock said drawers against sliding movement, and a locking cylinder integral with said horizontal arm of the L shaped bar and exposed through the side of the cabinet housing said drawers.

2. In a combination of the class described, a cabinet housing a series of sliding drawers, an L shaped bar, means mounting said bar for sliding horizontal movement in its own plane and with one arm in a horizontal position, the plane of said sliding movement being juxtaposed to the plane of the backs of the said sliding drawers, partitions between said drawers, means carried by said partitions for guiding said bar while preventing forceful pushing of said bar out of its plane of operation, locking extension pieces on said L shaped bar adapted to lock said drawers against sliding movement, a spring urging said L shaped bar out of drawer locking position, a locking cylinder integral with the horizontal arm of said L shaped bar, a sleeve-like housing secured to the side of said cabinet and through which the head of said locking cylinder protrudes, and means for locking said cylinder to said housing and with the L shaped bar secured in drawer locking position against the pressure of said spring.

3. In a combination of the class described, a cabinet housing a series of sliding drawers, partitions extending between said drawers, a back plate carried by said cabinet for preventing access to said drawers and partitions from the rear, a plurality of locking members movable as a unit in substantially a common vertical plane mounted between end surfaces formed on said partitions

and said back plate and in juxtaposed relation to the backs of said drawers, means carried by said partitions for guiding said locking members while preventing forceful pushing of said locking members out of said substantially common vertical plane, a locking cylinder secured to said locking members in the substantially common vertical plane of said locking members and extending through the side of said cabinet for operation, a sleeve-like cylinder housing secured to the said side of the cabinet for housing said cylinder, and means for locking said cylinder to said housing and with said locking members maintaining said drawers against outward movement.

4. In a combination of the class described, a cabinet housing having a series of sliding drawers, partitions between said drawers and extending beyond the backs of the said drawers, an L shaped bar, means mounting said bar for sliding movement in its own plane and with one arm in a horizontal position, the plane of said sliding movement being juxtaposed to the plane of the backs of the said sliding drawers and inwardly of the ends of said partitions, said partitions having horizontally extending slots formed therein for the vertical arm of said L shaped bar for allowing horizontal sliding of said bar, means whereby the vertical arm of said L shaped bar locks said drawers against sliding movement when said bar is in a predetermined position relatively to the horizontal, and a locking cylinder integral with said horizontal arm of the L shaped bar and exposed through the side of the cabinet housing for locking said bar in drawer locking position.

5. In a combination of the class described, a cabinet housing having a series of sliding drawers, partitions between said drawers, a locking bar having vertical and horizontal arms, means mounting said bar for sliding movement in its own plane and with one arm in a horizontal position, the plane of said sliding movement being juxtaposed to the plane of the backs of the said

sliding drawers, metal plates secured to said partitions and forming with the ends thereof horizontally extending slots for the guiding of the vertical arm of said locking bar and for allowing horizontal sliding of said bar while retaining said arm against pushing by any one of the drawers out of its operating plane, means whereby the vertical arm of said locking bar locks said drawers against sliding movement when said bar is in a predetermined position relatively to the horizontal, and a locking cylinder secured to the horizontal arm of said bar in the plane of said bar, and exposed through the side of the cabinet housing, said cylinder locking said bar in drawer locking position.

6. In a combination of the class described, a cabinet housing having a series of sliding drawers, partitions between said drawers and extending beyond the backs of the said drawers, a locking bar, means mounting said bar for sliding movement in its own plane and with one arm in a horizontal position and the other arm vertical, the plane of said sliding movement being juxtaposed to the plane of the backs of said sliding drawers and inwardly of the ends of said partitions, said partitions having horizontally extending slots formed therein for the vertical arm of said locking bar for allowing horizontal sliding of said bar, metal plates secured to said partitions and closing said slots whereby to retain said vertical arm against pushing by any of said drawers out of its operating plane, means whereby the vertical arm of said locking bar locks said drawers against sliding movement, a locking cylinder integral with the horizontal arm of said locking bar, a sleeve-like housing secured to the side of said cabinet and through which the head of said locking cylinder is operable, and means for locking said cylinder relatively to said housing and with the locking bar secured in drawer locking position.

JAMES C. SIEGEL.
